UNITED STATES PATENT OFFICE.

EDWARD G. SOLTMANN, OF NEW YORK, N. Y.

DESIGN FOR A T-SQUARE.

SPECIFICATION forming part of Design No. 19,044, dated April 9, 1889.

Application filed January 29, 1889. Serial No. 298,022. Term of patent 14 years.

To all whom it may concern:

Be it known that I, EDWARD G. SOLTMANN, a citizen of the United States, and a resident of New York, in the county and State of New York, have invented a new and original Design for a T-Square Head, of which the following is a specification.

My invention relates to a new design for T-squares, said design embodying certain novel features, as fully pointed out in the following specification and claim and illustrated in the accompanying drawings, in which—

Figure 1 represents a face view of a T-square embodying my design, and Fig. 2 a top view thereof.

Similar letters indicate corresponding parts. In the drawings, the letter A designates the head of a T-square surmounting the end of the blade, as usual. The outer edge of this head is bounded by ogee curves 1 2 3, an intermediate or central portion, 3 3, and a perfectly straight lower or inner edge, 1 1. The concave portions of the ogee curves begin at or near the end of the blade and terminate at the ends of the head, both the said portions

of the curves being of a small radius and consequently very deep and contrasting. The crowns of the convex portions are approximately on a level with the central portion, 3 3.

What I claim as my invention, and desire to secure by Letters Patent, is—

The herein-described design for T-squares, said design embodying a blade, a head surmounting the blade and having the deep ogee curves 1 2 3 on its outer edge and a perfectly straight lower or inner edge, said curves having their concave portions nearest the center and connected by an intermediate straight portion, 3 3, and their convex portions rising to approximately a level with the intermediate portion, substantially as shown and described.

In testimony that I claim the foregoing as my invention I have signed my name, in presence of two witnesses, this 16th day of October, 1888.

EDWARD G. SOLTMANN.
